(57) **CLAIM**

The ornamental design for a lunch box, as shown and described.

DESCRIPTION

FIG. 1 is a top perspective view of a lunch box design showing my new design.

FIG. 2 is a front view of a lunch box.

FIG. 3 is a rear view of a lunch box.

FIG. 4 is a left side view of a lunch box.

FIG. 5 is a right side view of a lunch box.

FIG. 6 is a top view of a lunch box.

FIG. 7 is a bottom view of a lunch box.

FIG. 8 is a bottom perspective view of a lunch box.

FIG. 9 is a perspective view thereof, showing the lunch box in an open state of use; and,

FIG. 10 is an enlarged view of a lunch box taken from the circle part in FIG. 6.

The broken lines in the drawings depict portions of the lunch box that form no part of the claimed design.
